Producers Association, Bradford, Pa., an unincor-
porated association

Application August 13, 1943, Serial No. 498,454

1 Claim. (Cl. 102—20)

1

This invention relates to well torpedoes for use in shooting wells, such as oil and gas wells and the like.

In well-shooting practice, different subterranean conditions require different concentrations of explosives opposite given sections of sand. Heretofore, this situation has been met by using torpedoes that have varied in diameter in accordance with the size of the explosive charge. This naturally resulted in the distance between the wall of the well and the torpedo varying with the size of the torpedo, and it is in this space that part of the energy of the shot is dissipated. The amount of such energy dissipation depends upon the distance the shock wave must travel, so an appreciable fraction of the explosive energy may be expended before the shock strikes the sand formation when there is a relatively wide space between torpedo and well wall.

It is among the objects of this invention to eliminate most of the energy loss due to the space between the torpedo and the well wall, and to hold the width of that space to a minimum regardless of the size of the explosive charge.

In accordance with this invention a well-shooting torpedo has a constant outer diameter, but it is provided with a central vertical passage the diameter of which depends upon the desired thickness of the explosive charge between the passage and the outside of the torpedo. This passage is adapted to be filled with a suitable incompressible material, such as sand or a liquid or both, so that all of the explosive energy is directed outwardly. The outer wall of the torpedo and the wall of the central passage may be formed by outer and inner shells of metal, plastic, or other suitable material, that form between themselves an annular chamber in which the explosive is disposed. The outer shells for these torpedoes are all the same size, but the inner shells have different diameters so that the explosive-receiving chambers can be varied in capacity for charges of different concentrations.

The invention is illustrated in the accompanying drawing in which Fig. 1 is a plan view of my torpedo with the top partly broken away; Fig. 2 is a vertical section taken on the line II—II of Fig. 1; Fig. 3 is a fragmentary vertical section through a modification of the invention; and Fig. 4 is a vertical section through another modification in which a solid or self-supporting explosive charge is used.

Referring to Figs. 1 and 2 of the drawing, the side wall of a well-shooting torpedo is formed by a cylindrical metal shell 1 of the maximum

2

diameter that can be used within safety limits. For all torpedoes that are to be used with well holes of the same diameter, the outer shells are the same size so that there will always be the same minimum annular space between the torpedo and well wall. The lower end of the shell is closed by an inverted conical member 2 the lower end of which is provided with a cylindrical extension 3 closed at its bottom. Rigidly mounted in the upper end of this extension is a nut 4 having a concave top. Inside the shell and concentric therewith there is a smaller inner shell 6 of substantially the same length as the outer one. The lower end of the inner shell is closed by an inverted conical member 7 which rests on conical member 2. The two shells are held together by a screw 8 projecting from the lower end of conical member 7 into nut 4. By this means the two shells are screwed together, thereby permitting

20 an inner shell of any desired diameter to be quickly mounted in fixed position in the outer shell. Of course, there are other ways by which the two shells can be connected, such as by welding or soldering them together.

25 The two shells having about the same length, and the inner shell being materially smaller than the outer one, the top of the inner shell lies below the top of the outer one to which it is connected by an inverted frusto-conical ring 9 having substantially the same degree of taper as conical member 2. This ring may be welded or soldered to the two shells. Due to the tapered lower end of the torpedo it can more readily be lowered into a well without interference from burrs on the well casing or from joints and other projections. The concave upper end of the torpedo permits two or more torpedoes to be nested on top of one another in a well. For lowering the torpedo into a well its upper end may be provided 40 with a bail or the like (not shown) to which a line can be attached.

45 The annular space between the two shells forms a chamber for an explosive 11 with which it is filled. The explosive charge may be any suitable material, but the annular chamber is particularly adapted to receive a liquid explosive, such as nitro-glycerine, that can be poured into the chamber through openings 12 in top ring 9. To prevent some of the force of the explosion from being expended inwardly, the passage through the inner shell is filled with substantially incompressible material such as a liquid, a solid (sand for example), or both, or some other type of solid material. The drawings show the inner shell 50 filled with sand 13. If desired, however, the in-

55

inner shell can be left empty, and it will become filled with the liquid standing in the well when the torpedo is lowered into the well.

It will be seen that although the outer shells of my torpedoes can always have the same diameter, the concentration of the explosive can be varied by having on hand a stock of inner shells of different diameters and using one that will form a charge-receiving space of the desired restricted capacity. Thus, the larger the inner shell the smaller the explosive charge. Nevertheless, in every case the explosive is always located the same distance from the wall of the well and can therefore be held right next to the formation where its energy should be expended.

Another advantage of always having an outer shell of maximum diameter is that it prevents the torpedo from becoming tilted in the well with a resulting unsymmetrical shooting action. With the shell nearly as large as the well hole, the torpedo can not become disposed in a lopsided position in the well.

Although the drawing shows the outer and inner shells concentrically arranged, it will be understood that if it is desired to shoot the formation harder in one direction than another, the inner shell can be mounted off-center relative to the outer one to give the charge-receiving chamber a varying width. Eccentric mounting of the inner shell is illustrated in Fig. 3.

In the modification shown in Fig. 3 the upper ends of the shells are connected in the same way as in Figs. 1 and 2, but the lower ends are joined in a different manner. Thus, the bottom of the outer shell 15 is secured to the top of an inverted, eccentric frusto-conical ring 16 of substantially the same size and shape as the top ring. The bottom of the inner shell 17 is open and is welded or soldered to the lower end of the ring to form an annular chamber in which the explosive 18 is retained. As in the previous embodiment, any size inner shell may be used, depending upon the size of explosive charge desired. The inner shell is shown as being mounted eccentrically of the outer shell so that the explosive chamber is wider at one side of the torpedo than at the opposite side. However, the two shells could be concentrically mounted if desired. This type of torpedo is especially designed for wells in which it will be immersed in a body of liquid, such as water or oil, standing in the well. Under such conditions it is not necessary to fill the central passage through the torpedo with an incompressible material, because when the torpedo is placed in the well the liquid therein will fill the inner shell.

If a solid, self-supporting explosive is used, the two shells are not necessary because the explosive can be pre-cast or molded to the desired external and internal diameters, and the central passage can then be filled with sand or the like. This modification is illustrated in Fig. 4 where the explosive was preformed into a ring 21 having an outer diameter of the proper maximum size, and having a central vertical passage

22 through it of the size necessary to leave just the desired amount of explosive in the ring. This passage may be coaxial with the ring or offset for unbalanced shooting as mentioned above. The passage may be packed full of sand or other dry, incompressible material to prevent the force of the explosion from acting inwardly, or it may remain empty until filled with liquid standing in a well into which it is lowered. If filled before being lowered, the filling material can be held in place by plugs or the like in the ends of the passage. Like the inner shell of Figs. 2 and 3, the size of central passage 22 can be varied to alter the concentration of explosive.

15 The way in which the torpedoes are detonated depends upon the type of explosive used as will be evident to those skilled in the art. As the manner of detonation has nothing to do with this invention, there is no illustration of it.

According to the provisions of the patent statutes, I have explained the principle and construction of my invention and have illustrated and described what I now consider to represent its best embodiment. However, I desire to have it understood that, within the scope of the appended claim, the invention may be practiced otherwise than as specifically illustrated and described.

I claim:

30 A well-shooting torpedo adapted to be lowered into a well, comprising a rigid outer cylindrical vertical shell having a diameter substantially as great as that of the well to be shot, a rigid cylindrical vertical shell mounted in fixed position 35 inside the outer shell and spaced therefrom to provide an annular charge-receiving space between the shells, the inner shell being large enough to restrict the size of said space to the desired capacity, means closing the bottom of 40 said space and the bottom of the inner shell, an explosive charge filling said space, and inert substantially incompressible material filling the inner shell to form a barrier to lateral pressure dissipation when the torpedo is discharged.
